Assign to

The Lowell Manufacturing Company.

Letters Patent No. 1899-Dated Feby. 16th 1864.

Design for a Carpet Pattern.

The schedule referred to in these Letters Patent and making part of the same.

To all whom it may concern:

Be it known that I, Elemir J. Key. of Lowell, in the County of Middlesex and State of Massachusetts, have originated and designed a new Pattern for Carpets or other fabrics, of which the following is a full, clear and exact description, reference being had to the accompanying drawings, making part of this specification.

The principal features of this design are two series of solid many sided blocks.

Small eight armed set figures, alternate with the blocks in both series.

The remainder of design consists of sections of vines arranged as shown in the drawings.

The colors employed for the different portions of the design, may be varied to suit the taste and wish of the manufacturer.

~Claim~

What I claim as my invention, and desire to secure by Letters Patent, is the Design or Pattern for Carpets or other fabrics, herein set forth.
